STRAP TENSIONING TOOL

Thomas J. Karass, 2450 Paton St., St. Laurent,
Quebec, Canada

Filed May 9, 1960, Ser. No. 60,507

Term of patent 14 years

(Cl. D54—13)

FIGURE 1 is a perspective view showing the front and one side of a strap tensioning tool embodying my new design.

FIGURE 2 is an elevational view showing the other side of the tool.

FIGURE 3 is a fragmentary view along the line III-III of FIGURE 2 with the handle and lever elements in cross-section to clarify the configuration details of said elements.

I claim:

The ornamental design for a strap tensioning tool, as shown.
